GARMENT CURING METHOD

Nishan S. Sarkisian, Mishawaka, Ind., assignor to
 Mishawaka Rubber and Woolen Manufacturing Company, Mishawaka, Ind., a corporation
 of Indiana

Application January 22, 1941, Serial No. 375,371

2 Claims. (Cl. 18—53)

My invention relates to the curing of raincoats and the like and has reference more particularly to a method whereby the upper part of the raincoat, including the neck and shoulder portions thereof, is maintained, during curing, in the same shape and form which it is to have in actual use.

The principal objects of my invention are to produce raincoats or the like more perfectly than heretofore; to insure correct size and shape of the neck, shoulders and other top portions of the raincoat; to hold the raincoat in a balanced upright position so that it hangs freely and evenly; and to avoid any distortions or strains while curing which would impart imperfections of shape and fit to the cured raincoat, these and other objects being accomplished as more fully described hereinafter and as shown in the accompanying drawing, in which:

Fig. 1 is a front view of a curing form constructed in accordance with my invention;

Fig. 2 is a rear view thereof;

Fig. 3 is a view looking at the left hand end of the form of Fig. 1;

Fig. 4 is a sectional view on the line 4—4 of Fig. 1; and

Fig. 5 is a view showing a raincoat hung on the form.

Referring to the drawing, the reference numeral 10 indicates the curing form as a whole which is made of sheet metal with an annular neck portion 11 extending upwardly and forwardly from the center of a transverse shell which is shaped to correspond to the upper portion of the human body. This shell is formed with rounded outwardly sloping shoulder portions 12 curved downwardly at their outer ends and with the portion 13 across the front, shaped to correspond to the upper part of the chest and the portion 14 across the back shaped to correspond to the upper part of the back. All of these portions 12, 13 and 14 extend downwardly to a point where the corresponding portion of the human body is substantially upright or devoid of any substantial slope so that a raincoat on the form is held distended at the top in substantially the same shape as when worn by a person and hangs freely therefrom. Preferably the bottom edge of the form is bent inwardly as indicated at 15 to reinforce the form and also to provide at this place a rounded surface which will leave no marking on the raincoat around the bottom of the form.

This form 10 is carried by a hanger 16 which may be of hook formation at its upper end, as

indicated at 17, for convenient suspension, and this hanger 16 extends downwardly through the neck portion 11 and is secured to the form by a strap 18 or in other convenient manner so that when the form is suspended by the hook 17 said form assumes the proper upright position to support a raincoat thereon in the natural position in which it would be worn.

This form 10 is made in various sizes to correspond to the sizes of the persons for whom the raincoats are intended and the outer surface is provided with an aluminum finish to prevent rubberized garments sticking thereto.

A number of these forms are provided, and in different sizes according to the quantity and sizes of raincoats to be produced and each assembled raincoat is mounted, as shown in Fig. 5, on a form 10 of the size corresponding to the size of the raincoat. The raincoat is adjusted on the form 10 so that it fits properly thereon and hangs freely and evenly therefrom, care being taken to see that it fits snugly about the neck portion 11 and elsewhere and the hanger with the raincoat thereon is then suspended in a vulcanizer and cured while mounted on the form.

Obviously in fitting the raincoat on its form, the material may be pressed against the form by hand or with a roller wherever required so as to fit the form and lie smoothly thereagainst and this form thus not only insures a perfect shaping of the top of the raincoat but maintains the lower hanging portions of the raincoat safely separated so that there is no danger that they may contact and adhere to one another. After the raincoat is cured, it may be readily removed from the form, because of the aluminum surfacing of the latter, and having been cured and given permanence in the form fitting shape it fits perfectly a person of the size of the form on which it has been vulcanized.

While I have shown and described my invention in a preferred form, I am aware that various changes and modifications may be made therein without departing from the principles of my invention, the scope of which is to be determined from the following claims.

I claim as my invention:

1. In the making of a vulcanized raincoat or the like, the steps of assembling the raincoat of unvulcanized vulcanizable material, applying the upper part of the raincoat on a form having only neck, shoulder, chest and back portions shaped to correspond respectively to the neck, shoulder, chest and back portions of the human body and of dimensions corresponding to a de-

sired size of raincoat leaving the remainder of the raincoat free of the form, pressing the upper portions of the raincoat against the form to conform said portions to the form, suspending the form with the raincoat thereon in a vulcanizer, and vulcanizing the raincoat.

2. In the making of a vulcanized raincoat or the like, the steps of assembling the raincoat of unvulcanized vulcanizable material, applying the upper part of the raincoat on a form having only neck, shoulder, chest and back portions shaped

to correspond respectively to the neck, shoulder, chest and back portions of the human body and of dimensions corresponding to a desired size of raincoat leaving the remainder of the raincoat free of the form, shaping the upper portions of the raincoat around the form in distended fashion substantially in the shape as when worn by a person, suspending the form with the raincoat thereon in a vulcanizer, and vulcanizing the raincoat.

NISHAN S. SARKISIAN.
